UNITED STATES PATENT OFFICE.

HANS GUSTAV BERENTSEN, OF NEW YORK, N. Y.

MARINE PROJECTILE.

1,294,605.

Specification of Letters Patent. Patented Feb. 18, 1919.

Continuation in part of application Serial No. 202,932, filed November 20, 1917. This application filed March 23, 1918. Serial No. 224,107.

To all whom it may concern:

Be it known that I, HANS GUSTAV BERENTSEN, a citizen of the United States of America, and a resident of New York, county and State of New York, have invented certain new and useful Improvements in Marine Projectiles, of which the following is a specification, reference being had to the accompanying drawings, forming

10 a part thereof.

My invention relates to shells and other projectiles and it has special reference to such as are adapted for marine warfare.

One object of my invention is to provide 15 a shell that shall be adapted for use against submerged bodies such as submarines or in operating against mine fields.

Another object of my invention is to provide a shell having means adapted to materially influence the trajectory of the shell 20 when it strikes the surface of the water, whereby the natural tendency of the shell to ricochet will be abrogated and furthermore the shell directed in a new but predetermined 25 course under the water.

Another object of my invention is to provide 30 a projectile having a screw member adapted to cause it to enter the water when it strikes the surface thereof together with means located or extending back of the center of gravity of the projectile for deflecting its trajectory and causing it to dive as soon as it enters the water.

Another object is to provide an attachment 35 for projectiles which may be arranged to be picked up as the projectile leaves the gun and shall be adapted to deflect the shell as it enters the water.

In attacking a submarine, submerged mine 40 or the like, if an ordinary shell is used it ricochets and is not effective unless it strikes the water at a large angle. If a shell having screw blades or a specially formed point of some other kind is used it 45 will either tumble end over end when it strikes the water or will continue in its course in the water.

Projectiles of this kind are not very effective against a submerged body because 50 the attacking gunner has, as a target, a periscope of a swirling water pool which shows on the surface the approximate location of the submerged body and if he hits the mark

on the surface, the projectile will pass harmlessly above the submerged body.

According to my invention the projectile is provided with means for causing it to dive as soon as it hits the water and consequently if the gunner hits the surface over the submarine the diving projectile will explode near the submerged body if properly timed.

In certain embodiments of my invention I provide in addition to the deflecting means or united with it, means such as a screw for 65 causing the rotating projectile to enter the water easily.

Other objects and advantages of my invention will be set forth hereinafter and I will now proceed to describe the same in 70 the following specification and then point out the novel features thereof in appended claims.

Referring to the drawings:

Figure 1 is a longitudinal sectional view 75 of a projectile constituting one embodiment of my invention.

Fig. 2 is a transverse sectional view taken on the line 2—2 of Fig. 1.

Figs. 3 and 4 are views corresponding respectively to Figs. 1 and 2 of another embodiment of my invention.

Fig. 5 is a partially sectional view of a gun, in which another form of projectile embodying my invention is disposed.

A projectile having a deflecting attachment in addition to a screw formation at the point is shown in partial longitudinal section in Fig. 6 and in transverse section in Fig. 7.

Figs. 8 and 9 are views corresponding to Figs. 6 and 7 showing another embodiment of my invention.

Fig. 10 shows a gun together with a support for holding the attachment of Figs. 8 95 and 9 in position at the muzzle of the gun.

Figs. 11 and 12 are partially diagrammatic elevations showing the trajectory of the projectiles of Figs. 6 and 8 and illustrating the manner in which they operate as 100 they strike the water and continue therein.

Special reference may first be had to Figs. 1 and 2 in which 10 designates a shell having a hollow body 11 adapted to contain a suitable charge of explosive 12, and a point or head 13. The hollow body has a cylindrical

portion 14 provided with bands 15 to co-operate with the rifling of the gun and a conical portion 16 which is usually smaller than the cylindrical portion forming therewith an annular shoulder 17 and tapering toward the point or head.

The head has radial blades 18 which are helically curved (see Fig. 2) and constitute a screw portion. It has a screw threaded 10 projection 19 which extends into the forward end of the conical portion of the body and has water passage 20 leading to a fuse plug 21.

The shoulder 17 serves to deflect the shell 15 and causes it to dive as it strikes the surface of the water, the screw blades 18 being adapted to prevent ricochetting.

The conical portion 16 may be a part of the head and be joined to the cylindrical 20 body as shown in Figs. 3 and 4 in which corresponding parts are designated by the same reference characters. In this arrangement the water passage to the fuse is axially arranged and extends to the nose of the shell.

25 The shell may be formed as shown in Fig. 5 and comprise a screw or propeller portion having blades 22 helically formed like the blades 18 of the previous figures, but located near the trailing end of the shell 30 and joined by a connective deflecting ring 23. If the propeller portion is permanently attached to or forms a part of the shell a special gun such as 24 with a large bore must be used. In this arrangement a light 35 cylindrical follower 25 is interposed between the shell and the explosive charge of the gun. When the gun is fired the shell is forced out at the usual high velocity and the follower 25, being light will drop harmlessly into the water at a relatively short 40 distance from the ship on which the gun is mounted. The ring has a band 26 which engages the rifling of the gun and causes the shell to rotate in the usual manner.

45 Instead of forming the shell as in Figs. 1 to 4 inclusive, a shell of usual shape and size may be provided as shown in Figs. 6 and 7 with screw blades 28 at the point and have a deflecting collar 29 mounted in position to be picked up by the shell as it leaves the gun (see Fig. 10 for example).

The collar 29 comprises a hub 30 which fits into the shell and a flange 31 which extends outwardly and backwardly behind the 55 center of gravity of the shell.

Referring to Figs. 8 and 9, 32 designates a shell of well-known construction, which is provided with a deflector attachment 33. This attachment comprises a hub 34, which 60 fits on to the shell, a plurality of screw propeller blades 35 and deflector ring 36. This structure is similar to that of Fig. 5, but the shell is adapted to be discharged from an ordinary gun, and the attachment which 65 combines the functions of deflector and

screw propeller is picked up by the shell as it leaves the gun.

The shell is provided with a band 37 which co-operates with the rifling of the gun in the usual manner, so that the shell 70 is rotated at high speed as it leaves the gun. The attachment of Figs. 8 and 9 offers much less resistance to flight through the air than that shown in Fig. 6, because the blades 35 are helically formed so that they cut a path, 75 due to the rotation of the shell. The ring 36 serves to cause the shell to dive as it strikes the surface of the water.

Furthermore, the blades offer small resistance to the movement of the shell in the 80 water, and consequently this form of attachment is particularly well adapted for shooting bodies submerged to a considerable depth below the surface of the water, as well as for those which are nearer the sur- 85 face.

Either of the forms of attachment shown in Figs. 6 and 8 is adapted to deflect the shell into a definite course downwardly, as it strikes the water but there will be a 90 certain amount of drift due to the kinetic forces and this is indicated by the two sets of broken lines in Figs. 11 and 12, one set of lines indicating the theoretic projectory of the shell in the water, and the other the 95 actual projectory.

Fig. 11 clearly indicates the operation of a shell such as that shown in Fig. 6 as it strikes the surface, and Fig. 12 similarly illustrates the action of a shell such as that 100 shown either in Figs. 8 and 9, or that shown in Fig. 5.

The action of the shells of Figs. 1 to 4 inclusive is similar and the drawings serve to illustrate the action of any embodiment 105 of my invention having a rigid deflector which is effective back of the center of gravity of the shell, or having such a deflector in combination with a screw portion which materially assists in overcoming the 110 tendency of the shell to ricochet.

Any suitable means may be used to support the attachments at the muzzle of the gun, for example. A yoke 38 may be provided as shown in Fig. 10 with a segmental 115 clamping ring 39 which is adapted to be bolted to the gun. The yoke comprises an annular carrier 40 into which the attachment is loosely fitted against a stop projection 41. A spring clip 42 holds the attachment in place until it is picked up by the shell as it leaves the gun.

This application is a continuation in part of my application Ser. #202932 filed November the 20th, 1917, claims covering all the 125 embodiments above mentioned being included in this application together with specific claims to the shells shown in Figs. 1 to 4 inclusive, and 6 and 7, while the claims covering the attachments and their sup- 130

ports as a separate species are being retained in my copending application above referred to.

What I claim is:

- 5 1. A marine projectile comprising a cylindrical body portion adapted to fit the bore of a gun, a tapering leading portion connected to the cylindrical body portion and forming therewith an annular deflecting shoulder back of the center of gravity of the shell.
- 10 2. A marine projectile comprising a cylindrical body portion adapted to fit the bore of a gun, a tapering leading portion connected to the cylindrical body portion and forming therewith an annular deflecting shoulder back of the center of gravity of the shell, and a screw or propeller member for causing the shell to enter the water.
- 15 3. A marine projectile comprising a cylindrical body portion adapted to fit the bore of a gun, a tapering leading portion connected to the cylindrical body portion and forming therewith an annular deflecting shoulder back of the center of gravity of the shell, and propeller blades at the point.
- 20 4. A marine deflector for shells comprising rigid means which is effective behind the center of gravity of the shell for deflecting the course of the shell when it strikes the surface of the water.
- 25 5. A marine deflector for shells comprising a hub adapted to fit the shell, and rigid means which is effective behind the center of gravity of the shell for deflecting the course of the shell when it strikes the surface of the water.
- 30 6. A marine collar for shells comprising a hub adapted to fit the shell, and a rigid deflector extending outwardly from the hub, behind the center of gravity of the shell.
- 35 7. A marine collar for shells comprising a hub adapted to fit the shell, and a rigid flange extending outwardly behind the center of gravity of the shell for deflecting the course of the shell when it strikes the surface of the water.
- 40 8. A marine collar for shells comprising a hub adapted to fit the shell, and a symmetrical flange extending outwardly and backwardly behind the center of gravity of the shell from the hub for deflecting the course of the shell when it strikes the surface of the water.
- 45 9. A marine projectile comprising a shell and means extending back of the center of gravity of the shell and attached thereto for effecting a predetermined deflection of the trajectory when the shell strikes the surface of the water at an angle to the surface thereof.
- 50 10. A marine projectile comprising a shell, and means extending back of the center of gravity of the shell for effecting a predetermined deflection of the trajectory when the shell strikes the surface of the water at an angle to the surface thereof.
- 55 11. A marine projectile comprising a shell adapted to be discharged from a rifle, having a screw member arranged to cause the rotating shell to enter the water and means back of the center of gravity for deflecting the projectile to a predetermined course in the water.
- 60 12. A marine projectile having a portion adapted to engage the rifling of the gun, a screw portion adapted to cause the projectile to enter the water when it strikes the surface thereof, and means back of the center of gravity for deflecting the projectile to a predetermined course.
- 65 70 75 80 In witness whereof, I have hereunto set my hand this 22nd day of March, 1918.

HANS GUSTAV BERENTSEN.
